United States Patent Office

Des. 188,514
Patented Aug. 2, 1960

188,514

TYPEWRITER

Carl W. Sundberg, Bloomfield Hills, and Montgomery
Ferar, Huntington Woods, Mich., assignors to Sperry
Rand Corporation, New York, N.Y., a corporation of Delaware

Filed Sept. 15, 1959, Ser. No. 57,570

Term of patent 14 years

(Cl. D64—11)

Des. 188,514

PAGE 2

FIG. 2

Fig. 1 is a left front perspective view of a typewriter showing our new design:

Fig. 2 is a right front perspective view, some of the keys and part of the space bar having been eliminated for convenience of illustration; and

Fig. 3 is a rear elevational view thereof.

We claim:

The ornamental design for a typewriter, as shown and described.
